UNITED STATES PATENT OFFICE.

CHARLES WITTECK, OF NEW YORK, N. Y., ASSIGNOR TO DOMINICK & HAFF,
OF SAME PLACE.

DESIGN FOR A FORK-HANDLE.

SPECIFICATION forming part of Design No. 16,412, dated December 8, 1885.

Application filed October 13, 1885. Serial No. 179,819. Term of patent 14 years.

To all whom it may concern:

Be it known that I, CHARLES WITTECK, of the city, county, and State of New York, have invented and produced a new and original 5 Design for a Fork-Handle, of which the following is a specification, reference being had to the accompanying drawings, forming part thereof.

Figure 1 is a front view of my newly-designed fork-handle, and Fig. 2 is a view of the back of the same, these two views being deemed necessary to fully illustrate my design.

The leading feature of my design consists in 15 a shell-shaped ornament located just above the handle proper on the face of a crown-like projection which extends from the upper end of said handle.

A is the handle, formed with a crown-like 20 projection, B, substantially in the form shown in the figures hereinbefore referred to. Upon the face of the crown B there is a shell-shaped ornament, C, consisting of a number of scallops radiating from a common center. The 25 edges of the handle are formed with a thread,

D, which widens at the broadest part of the handle and extends downward on either side thereof and merges with the edges of the bowl. The faces N of the handle, between the threads D, are convex and terminate in decided elevations, which are shown at *a a*. Below the rounded point *a* on the back of the spoon or fork there is a second shell-shaped ornament, E.

This design, although described in connection with a fork-handle, is of course equally applicable to a knife or spoon handle.

I claim—

1. The design for a fork-handle herein shown and described, the same consisting of 40 the shell C upon a crown, B, above the body of the handle, convex faces N, and points *a a*.

2. The design for a fork-handle herein shown and described, the same consisting of 45 the shell C upon a crown, B, threads D, convex faces N, points *a a*, and shell E.

CHARLES WITTECK.
